FIG. 1

FIG. 3

FIG. 4

INVENTOR
KENNETH E. LYMAN
BY

J. W. McConkey

ATTORNEY

UNITED STATES PATENT OFFICE

KENNETH E. LYMAN, OF CHICAGO, ILLINOIS, ASSIGNOR TO BENDIX BRAKE COMPANY, OF CHICAGO, ILLINOIS, A CORPORATION OF ILLINOIS

BRAKE

Application filed July 16, 1927. Serial No. 206,152.

This invention relates to brakes and is illustrated as embodied in an internal expanding brake for an automobile. An object of the invention is to provide simple means for adjusting the brake, preferably automatically.

In one desirable arrangement the brake includes a pair of shoes arranged end to end, and one of which is preferably anchored, 10 and which are connected by a novel joint which can be adjusted to separate the shoes to compensate for wear.

In the illustrated embodiment the joint between the shoes includes a cam which is 15 adjusted angularly to provide the adjustment and which I prefer to arrange for movement about a radial axis extending between the ends of the shoes.

I also prefer to provide at the above-described joint a stop for determining the idle positions of the shoes and which is preferably arranged to prevent lateral movement of the shoes.

The above and other objects and features 25 of the invention, including various novel and desirable details of construction, will be apparent from the following description of one illustrative embodiment shown in the accompanying drawing, in which:

Figure 1 is a vertical section through the 30 brake just inside the head of the brake drum and showing the brake shoes in side elevation;

Figure 2 is a partial section on the line 35 2-2 of Figure 1 and showing the adjusting means;

Figure 3 is a partial section on the line 3-3 of Figure 1, showing the arrangement of the cam; and

Figure 4 is a perspective view of one end of one of the brake shoes showing its formation 40 for engagement with the cam.

In the arrangement illustrated, the brake includes a rotatable drum 10 at the open side 45 of which is a backing plate 12 and within which are arranged three brake shoes 14, 16, and 18. The shoes are applied by a device such as a double cam 20 against the resistance of a main return spring 22, which urges 50 the shoes 14 and 18 away from the drum, and

a secondary return spring 24 which urges the shoe 16 away from the drum. The shoe 14 is anchored at its lower end on a fixed pivot 26 while the shoe 16 is forked at its end to straddle the end of the shoe 14 and is anchored on a fixed pivot 28.

The present invention has to do with adjusting the brake by separating more or less the shoes 16 and 18 or their equivalents, by a novel floating joint between the shoes and through which the shoe 18 acts to force the shoe 16 against the drum to apply the brake.

In the particular embodiment illustrated, each of the shoes 16 and 18 is formed at its end with a groove 30 for a cam 32 rotatably mounted in a carrier 34 between the ends of the shoes and moving with the shoes when the brake is applied and released. The carrier 34 is provided with a device such as a finger 36 engaging a groove 38 is an eccentric 40 adjustably clamped by a nut 42 to the backing plate 12. The finger 36 is urged toward the bottom of the groove 38 by spring 24 so that the eccentric 40 serves as a stop 70 adjustably positioning the shoe when the brake is released. The finger 36 also interlocks with the walls of the groove 38 to prevent lateral movement of the adjacent ends of the shoes 16 and 18.

One end of the spindle of the cam 32 projects through the carrier 34 and has secured thereon a segmental rack 44 normally held stationary by a spring locking pawl 46, and which is engaged on the application of the brake after excessive wear by a stationary 85 spring pawl 48 secured to the backing plate 12. If there has been excessive wear in the brake the pawl 48 causes the rack 44 to shift one tooth when the brake is applied, thus turning the cam 32 to separate the shoes 16 and 18 to compensate for the wear.

While one illustrative embodiment has been described in detail, it is not my intention to limit the scope of the invention to that particular embodiment or otherwise than by 90 the terms of the appended claims.

I claim:

1. A brake comprising, in combination, an anchored shoe and an unanchored shoe arranged end to end, a joint connecting said 100

shoes, and means for automatically adjusting said joint to separate the shoes to compensate for wear.

2. A brake comprising, in combination, an anchored shoe and an unanchored shoe arranged end to end, a joint connecting said shoes and including a floating cam between the shoes, and means for turning said cam to separate the shoes to compensate for wear.

10 3. A brake comprising, in combination, an anchored shoe and an unanchored shoe arranged end to end, a joint connecting said shoes, and means for automatically adjusting said joint to separate the shoes to compensate for wear, said means including a ratchet moving with the joint and a stationary pawl operatively engageable with the ratchet and shifting the ratchet in case of excessive wear of the shoes.

20 4. A brake comprising, in combination, a pair of shoes arranged end to end, and a floating joint between the shoes including a cam engaging the adjacent ends of the shoes and arranged with its axis extending radially between said ends.

25 5. A brake comprising, in combination, a pair of shoes arranged end to end, and a floating joint between the shoes including a cam engaging the adjacent ends of the shoes and arranged with its axis extending radially between said ends, and said ends being grooved to embrace the cam.

6. A brake comprising, in combination, a drum, an anchored and an unanchored shoe arranged end to end within the drum and connected at their adjacent ends by a floating joint, means engaging the unanchored shoe at its free end to apply said shoes to the drum, and means engaging the floating joint between said shoes to automatically take up for wear of the shoes.

7. A brake comprising, in combination, a drum, an anchored shoe and an unanchored shoe arranged within said drum and connected end to end by a floating joint, means engaging the unanchored shoe at its free end to apply said shoes to the drum, a backing plate, and means extending through the backing plate and coupled with the floating joint to adjustably position the shoes.

8. A brake comprising, in combination, a drum, an anchored shoe and an unanchored shoe arranged within the drum and connected end to end by a floating joint, means engaging the free end of the unanchored shoe to apply said shoes to the drum, and means including a rotatable cam positioned between the ends of said shoes and operable to adjustably position the shoes.

60 9. A brake comprising, in combination, a drum, a backing plate, a pair of brake shoes arranged end to end within the drum and connected by a floating joint, means operatively engaging one end of one of the shoes 65 to apply both shoes to the drum, and means

carried by the backing plate operatively engaging the floating joint between the shoes to adjustably position the shoes.

10. A brake comprising, in combination, a drum, a backing plate, a pair of brake shoes arranged end to end within the drum and connected by a floating joint, means operatively engaging one end of one shoe to apply said shoe to the drum and through said floating joint to apply the other shoe to the drum, and means operatively engaging said floating joint to adjustably position the shoes.

11. A brake comprising, in combination, a drum, a backing plate, a pair of brake shoes arranged end to end within the drum and connected by a floating joint, means operatively engaging one end of one shoe to apply said shoe to the drum and through said floating joint to apply the other shoe to the drum, and means operatively engaging said floating joint to automatically actuate the same to take up for wear of the shoes.

12. A brake comprising, in combination, a drum, a pair of brake friction members arranged end to end therein, and a part positioned between the adjacent ends of said friction members and rotatable about an axis extending radially of the drum to adjustably position said members, said part being held by said shoes against displacement radially thereof.

13. A brake comprising, in combination, a drum, a pair of brake friction members arranged end to end therein, and a part positioned between the adjacent ends of said friction members and rotatable about an axis extending radially of the drum to adjustably position said members, said part being held by said shoes against displacement radially thereof, and means engaging said part and automatically operable to rotate the part to take up for wear of the friction members.

14. A brake comprising, in combination, a drum, a backing plate, a pair of brake friction members arranged end to end within the drum, means positioned between the ends of said friction members and having a part rotatable about an axis extending radially of the drum to adjustably position said members, automatically operable mechanism coupled with said part to rotate the part to take up for wear of the friction members and an eccentric rotatably supported upon the backing plate and coupled with said means and operable to adjustably position said members.

In testimony whereof, I have hereunto signed my name.

KENNETH E. LYMAN.
